SHUTTLE MOTION

Antonio Schiappa, Pawtucket, R. I.

Application June 22, 1955, Serial No. 517,111

6 Claims. (Cl. 139—138)

This invention relates to improvements in shuttle motions and more particularly to the shuttle motion in a narrow fabric loom.

One of the objects of the present invention is to provide an improved shuttle motion for a narrow fabric loom.

Another object of the present invention is to provide an improved shuttle motion for a narrow fabric loom which has fewer parts, improved shuttle motion control and the almost complete elimination of loom smashes.

Narrow fabric looms are customarily made with a lay having a rack rod movable longitudinally therein and meshing with pinions which in turn have driving relation with racks on the shuttles. As the rack rod is moved in one direction lengthwise of the lay the pinions are rotated and cause movement of the shuttles in the opposite direction through the warp threads and across the fabric space. The rack rod moves in a straight line and is moved positively back and forth by mechanical devices on opposite ends of the loom which must be synchronized in accurate timed relation.

In the past the mechanical devices consisted of shuttle pulleys, shuttle straps, shuttle pulley stands and lay-wires. The present invention eliminates these devices and the need of mechanism on both ends of the loom. This removes the need of accurate timing of devices on opposite ends of the loom and the consequent smashes when the timing was off.

A further object of the present invention is the elimination of break down time and loom idleness due to smashes, which originate in part in the stretch of shuttle straps and lay wires.

And still another object of the present invention is the elimination of leather shuttle straps and the consequent faulty work produced by the loom due to the stretch of the leather which resulted in failure to pull the rod rack the desired distance.

Other objects of the present invention will become apparent in part and be pointed out in part in the following specification and claims.

Referring to the drawings wherein similar characters of reference indicate corresponding parts in all the figures:

Figure 1 is a perspective view of the new and improved shuttle motion.

Figure 2 is a plan view of the lay, rack rod and shaft of the new shuttle motion.

Figure 3 is a side elevational view of the new shuttle motion.

Figure 4 is a perspective view of a modified form of drive connection.

Figure 5 is a plan view of a drive connection of the new shuttle motion.

Figure 6 is a rear elevational view of another drive connection of the new shuttle motion.

Figure 7 is a transverse sectional view taken along line 7—7 of Figure 2.

In proceeding with this invention reference is made to the narrow fabric loom frame 11 and the crown gear 12

2

which has its bearing in frame 11 and is driven in a manner well known to the Crompton-Knowles narrow fabric loom of which it is a standard part.

A crank pin 13 is fixed to the spokes of crown gear 12. 5 Shaft 14 of crown gear 12 projects outwardly from frame 11 and has a crank 15 provided with arms 16 and 17 mounted for independent rotation thereon. Elongated slots 18 and 19 are provided in arms 16 and 17 respectively. Crank pin 13 engages elongated slot 16 to drive 10 crank 15. A universal joint is provided consisting of an arm 20 integrally formed with the lower part 21 of a bearing, the upper part 23 of which is bolted by means of bolts 24 to lower part 21 and to a shaft 9 which is threaded on opposite ends to accommodate nuts 27 and 28. 15 A pillow block 25 provided with teeth 29 in one face is slidably mounted on the shaft 9. Arm 17 is provided with teeth 26 which are engageable with teeth 29. A washer 39 is placed on the shaft between nut 28 and pillow block 25. The turning of nuts 27 and 39 forces bearing 21, 23 against pillow block 25 and the engagement of teeth 26, 29 so that the shaft 9 is firmly but adjustably held in arm 17.

A yoke 30 is pivotally connected to arm 20 by means of pin 31. A collar 32 integrally formed with yoke 30 is provided with an internal thread. A connecting link 33 is provided with threads 34 which engage the internal threads in collar 32 and are secured against working apart by means of a lock nut 35.

The lay 40 has slidably mounted therein a rack rod 42 which meshes with the pinions for the shuttles and is arranged for longitudinal reciprocation along the lay to cause the pinions to rotate first in one direction and then in the other. This is common construction in a narrow fabric loom and of itself forms no part of the present invention.

A bracket 41 is secured to the lay 40 by means of bolts 79. A swivel bearing 43 is secured to bracket 41 by means of nut and bolt combinations 44, 45. The picker motion rod 36 secured by means of bolt 100 to picker motion jack 37 having a base 38 which rests on the mill floor is standard construction in Crompton-Knowles narrow fabric looms. A block 46 provided with a bearing 47 is secured to base 38 by means of bolt 101. A lay sword shaft 103 is mounted in bearing 47. A collar 48 is fixed to lay sword shaft 103. A lay sword (not shown) rocks lay sword shaft 103, collar 104 and lay 40. The lay sword (not shown) and lay sword shaft 103 are standard construction of a Crompton-Knowles narrow fabric loom and as such are well known in the art. 50 A shaft 48 is seated in collar 104 and is mounted in swivel bearing 43.

A bracket 50 having a depending arm 51 is fixed to shaft 48. A plate 52 having projection 54 is (see Figure 6) adjustably secured to arm 51 by means of nuts and bolts 53 which pass through an elongated slot in arm 51. A stub shaft 55 is fixed in projection 54. A block 56 is pivotally connected to stub shaft 55. A yoke 60 provided with a collar 61 having internal threads is pivotally connected to block 56 by means of a pin 63 to form a universal joint. Connecting link 33 is provided with threads 64 which engage the internal threads in collar 61. Threads 61, 64 are secured from working apart by means of lock nut 65.

A lever arm 66 provided with a series of holes 67 is secured to shaft 48. A plate 70 having teeth which engage the recesses in the rack rod 42 lays on said rack rod 42. An intermediate member 71 is recessed to accommodate and lay on top of plate 70. A U-shaped covering 72 provided with a cross member 73 straddles rack rod 42 and plate 70. A series of pins 74 positioned in the legs of the U of covering 72 underlie rack rod 42. Two screws 75, 76 provided in covering 72

abut the top of intermediate member 71. Screws 75, 76 force intermediate member 71 against plate 70 which abuts rack rod 42 to force rack rod 42 against pins 74 to provide a construction which allows cross member 73 to be adjustably positioned along rack rod 42.

A connection is provided consisting of a shaft 106 which is pivotally mounted in cross member 73 and a rod 77. A second connection 78 is provided consisting of a threaded member 80 and a rod 81. Threaded member 80 engages one of the series of holes 67 and is secured therein by means of a nut 82. A split tube 83 houses rods 77 and 81. Two couplings 85, 86 secured split tube 83 to rods 77, 81 to form a tie rod.

Referring to Figure 4 wherein is shown a modified form of drive connection which may replace the universal joint comprising arm 51, plate 52, etc., by providing a bevel gear 90 fixed to shaft 48 and a companion bevel gear 91 loosely mounted on lay sword shaft 103. A lever arm 93 is fixed to bevel gear 91. Yoke 60 is pivotally secured to lever arm 93 by means of pin 95.

In operation crown gear 12 will be rotated in a manner well known to the Crompton-Knowles narrow fabric loom. Rotation of crown gear 12 will carry with it crank pin 13 which will rotate crank 15 with arms 16, 17. Rotation of arm 17 will carry with it bearing 21, 23 and arm 20 which will cause connecting link 33 to reciprocate in a crank type motion. Connecting link 33 through yoke 69, arm 51 and plate 52 will rock shaft 48 whereby lever arm 66 reciprocates through an arc carrying with it split tube 83 and rods 81, 77. Rod 77 through cross member 73 will reciprocate rack rod 42.

It will be noted that the position for reciprocation of rack rod 42 is adjustably controlled through split tube 83 which allows rods 81, 77 to be adjustably inserted lengthwise. Holes 67 adjust the throw of split tube 83 through lever arm 66. Nuts 53 allow an adjustment of plate 52 which influences the throw of yoke 60. And the adjustment of arm 20 through the shaft in bearing 21, 23 in arm 17.

Connecting link 33 through lever arm 93 will transfer the motion of crank 15 to bevel gear 90 and shaft 48.

Having shown and described preferred embodiments of the present invention, by way of example, but realizing that structural changes could be made and other examples given without departing from either the spirit or scope of this invention.

What I claim is:

1. In a narrow fabric loom having a crown gear, and a rocking lay, a rack rod reciprocatingly mounted in said lay, a crank drive driven by said crown gear, a bracket secured to said rocking lay, a swivel bearing mounted in said bracket, a substantially vertical shaft mounted in said swivel bracket, means connecting said vertical shaft with said rack rod and a second means connecting said vertical shaft with said crank drive whereby said crank drive reciprocates said rack rod through said vertical shaft and said rocking lay through said bracket and swivel bearing rocks said vertical shaft.

2. In a narrow fabric loom having a crown gear, a rocking lay, a rack rod reciprocatingly mounted in said lay, a crank drive driven by said crown gear, a substantially vertical shaft having an arm fixed to its upper end and having means on its lower end to provide a connection with said crank drive to reciprocate said vertical shaft, a bracket secured to said lay, a swivel bearing located in said bracket, said vertical shaft being mounted in said swivel bearing, a tie rod connecting said arm with said rack rod whereby said crank motion through said vertical shaft reciprocates said rack rod and said rocking lay through said bracket and swivel bearing rocks said vertical shaft.

3. In a narrow fabric loom having a crown gear, a rocking lay and a picker motion rod bracket, a rack rod reciprocatingly mounted in said lay, a crank drive driven by said crown gear, a substantially vertical shaft, a

bracket secured to said lay, a swivel bearing mounted in said bracket, a second bearing mounted on said picker motion rod bracket, said vertical shaft being mounted for reciprocating movement in said swivel bearing and said second bearing a bevel gear fixed to said vertical shaft, a second bevel gear meshing with said first bevel gear and reciprocatingly mounted in said second bearing, a first means connecting said second bevel gear with said crank motion to reciprocate said vertical shaft and a second means connecting said vertical shaft with said rack rod to reciprocate said rack rock.

1   4. In a narrow fabric loom having a crown gear, a rock-
ing lay, and a picker motion rod bracket, a rack rod re-
ciprocatingly mounted in said lay, a crank drive driven by
15   said crown gear, a substantially vertical shaft having an
arm fixed to its upper end and a second arm adjacent its
lower end, a bracket fixed to said lay, a swivel bearing, for
the upper end of said shaft, mounted in said bracket, a
second swivel bearing on the lower end of said shaft
20   mounted in said picker motion rod bracket, a connecting
link, a universal joint uniting said connecting link with
said crank drive, a second universal joint uniting said con-
necting link with said second arm and a tie rod connecting
said rack rod with said arm fixed to the upper end of said
25   shaft.

5. In a narrow fabric loom having a crown gear, a rocking lay and a picker motion rod bracket, a rack rod mounted for reciprocating motion in said lay, a crank drive driven by said crown gear including an arm having an elongated slot, a horizontal shaft adjustably secured in said slot, a second arm integrally formed as part of a bearing, said bearing being secured to said horizontal shaft, a substantially upright shaft having a third arm fixed to its upper end, a fourth arm fixed to the lower section of said upright shaft, a bracket fixed to said lay, a swivel bearing mounted in said bracket, the upper end of said upright shaft being mounted for rocking motion in said swivel bearing, a second swivel bearing mounted in said picker motion rod bracket, the lower end of said upright shaft being mounted in said second swivel bearing, a connecting link having a yoke on one end, said yoke being pivotally connected to said second arm, a universal joint connecting said connecting link with said fourth arm, and a tie rod adjustably and pivotally connecting said third arm with said rack rod.

45 said rack rod.

6 In a narrow fabric loom having a crown gear, a rock-
ing lay and a picker motion rod bracket, a rack rod
mounted for reciprocating motion in said lay, a crank
drive driven by said crown gear including an arm having
an elongated slot, a horizontal shaft adjustably secured in
said slot, a bearing, a second arm integrally formed as part
of said bearing, said bearing being secured to said hori-
50 zontal shaft, a vertical shaft having a third arm fixed to its
upper end and a fourth arm fixed to its lower end, a
bracket secured to said rocking lay, a swivel bearing
55 mounted in said bracket, the upper section of said vertical
shaft being mounted for rocking and reciprocating
motion in said swivel bearing, a second swivel bearing
mounted in said picker motion rod bracket, the lower sec-
60 tion of said vertical shaft being mounted for rocking and
reciprocating motion in said second swivel bearing, a con-
necting link having a yoke on one end pivotally connected
to said second arm, a universal joint connecting said con-
necting link with said fourth arm, a tie rod consisting of
65 a first rod adjustably connected to said third arm and a
second arm, a split tube adjustably connecting said first
and second rods, a cross member adjustably secured to
said rack rod and said second rod pivotally connected to
said cross member.
